Primary Examiner — Samantha Wood

Assistant Examiner — Emily A Caven

(57) **CLAIM**

The ornamental design for a cat tree, as shown and described.

DESCRIPTION

FIG. 1 is a perspective view of a cat tree showing my new design.

FIG. 2 is a front view of a cat tree.

FIG. 3 is a rear view of a cat tree.

FIG. 4 is a left side view of a cat tree.

FIG. 5 is a right side view of a cat tree.

FIG. 6 is a top view of a cat tree; and,

FIG. 7 is a bottom view of a cat tree.

The broken lines depict portions of the cat tree that form no part of the claimed design.

1 Claim, 7 Drawing Sheets
